UNITED STATES PATENT OFFICE

CHRISTIAN N. BERGMANN, OF PITTSBURGH, PENNSYLVANIA, ASSIGNOR TO BERGMANN
PACKAGING MACHINE COMPANY, OF PITTSBURGH, PENNSYLVANIA, A CORPORA-
TION OF DELAWARE

ELASTIC BAND CUP DISPENSER

Application filed October 9, 1928. Serial No. 311,362.

My invention refers to improvements in dispensing holders for receptacles, as paper cups. The improvement refers particularly to an adjustable thin rubber ring, so combined with the lower end of a delivery tube as to provide a central variable diameter elastic rim opening, providing for support of a stack of nested cups or the like, and permitting of removal of the lowermost cup 10 successively by mere downward withdrawal.

In devices utilizing elastic open center diaphragms, such as shown in the prior patent of Gilchrist #1,155,562, and similar constructions, elastic perforated diaphragms 15 have been used having holes of different diameters to dispense cups or cones of markedly different sizes, and such diaphragms have been fixedly mounted on and attached to the lower end of the dispensing tube by 20 a surrounding frame which, in effect, becomes a rigid marginal part of the diaphragm.

In my invention I utilize a section of thin rubber tubing having sufficient elasticity for 25 ample stretching and maximum tension, allowing it to be drawn upwardly around the lower end of the dispensing tube more or less, so as to extend inwardly toward the center by a variable width rim portion, surrounding a correspondingly variable size central opening, and with correspondingly variable reduced tension, for different diameters of cups, etc.

In the drawings showing one preferred 30 embodiment of the invention:

Fig. 1 is a vertical sectional view showing the lower end of a dispensing tube provided with my improvement, adjusted to dispense a maximum diameter cup or receptacle;

Fig. 2 is a similar view showing the elastic band adjusted slightly downwardly and inwardly across the end of the tube for an intermediate size cup or receptacle;

Fig. 3 is a similar view showing the elastic band adjusted further down with a correspondingly reduced middle opening for a minimum size cup or receptacle;

Fig. 4 is a cross sectional view on the line IV—IV of Fig. 1;

Fig. 5 is a perspective detail view of the

elastic band, detached and contracted to its normal size;

Fig. 6 is a similar view showing the elastic band in the position assumed when it is in operative position around the bottom 55 of the dispensing tube.

Referring to the drawings, 2 is the dispensing tube which may be of any desired length, mounted or supported in any convenient way, adapted to receive a nested 60 stack of tapered cups 3 or the like for free delivery downwardly through the tube, as the lowermost receptacle is removed. Cups 3, which are in large common use for drinking purposes, ice cream, etc., are comparatively light and flexible, and are usually provided at their upper edges with a laterally extending rim 4. Tube 2 is of a size to freely admit the largest diameter of cup 65 for gravitating movement downwardly, and is unprovided with any additional attachment other than the elastic tubular band 5. The tube 2 is preferably rounded at its lower outer annular edge, as at 6, to facilitate 70 application and prevent injury to the elastic band.

Band 5, of freely elastic thin rubber, either originally made for such purpose, or in the form of a section of inner tubing or the like, is of a normal diameter, the same 80 or slightly less than that of the resulting supporting opening within the horizontally arranged tensional edges, when the tube is applied.

In adapting the band 5 for proper functioning, it is stretched upwardly over the end of the tube 2, the elasticity of the band effecting a tight adhesion around the tube. As applied, the band is materially stretched 85 and adjusted until the opening surrounded by the inwardly extending terminal annular edge 7 is enlarged to a diameter slightly less than that of the upper rim portion of the cup 3, when it is in position for operation with such particular size of cup. Care should be observed in applying the elastic ring 5 so that it will be stretched evenly 90 around the center of the tube, providing the inwardly extending concentric edge 7, equal- 95

ly spaced around the middle clearance opening for the cups.

Thereupon, a stack of cups being deposited in the upper portion of tube 2, they will fall downwardly with the lowermost cup extending through such opening, and being held, together with all of the superimposed cups, by the elastic rim 7.

Thereupon, the lowermost cup may be 10 freely drawn downwardly by the hand through the opening and past the supporting elastic rim, leaving the next adjacent cup supported in the same manner.

Such operation may be continued by 15 removing each lowermost individual cup in the same manner, until the stack is exhausted.

When it is desired to utilize the invention for a medium size cup, as in Fig. 2, the 20 elastic band 5 is lowered proportionately, with an inward proportional contraction of the terminal annular lip member 7, when a stack of such medium size cups may be deposited for support and individual extraction in the same manner.

When minimum size cups are used, as in Fig. 3, the band 5 is adjusted further down with corresponding inward contraction of the lateral lip portion 7, with capacity for 30 support and removal in the same manner as above described.

It will be observed that with the largest size cups of greatest circumference and ample peripheral flexibility, the tension of the 35 band will be at its maximum, as to the comparatively narrow supporting lip portion 7. As the diameter and circumference of the cups reduce, the inwardly contracted lip portion 7 slightly reduces in tension and increases in pliability, such action continuing as the size and weight of the cups are reduced through any intermediate grades, to the minimum size. It will be therefore clear that the device automatically accommodates 40 itself to the varying conditions of the cups or receptacles so that each size may be supported and removed with equal facility, and just the necessary degree of supporting resistance to facilitate easy removal.

50 The diameter of tube 2 is ordinarily unvarying, and while with the maximum size cups they will be accurately guided and maintained in vertical alinement within the tube, smaller sizes may be used with equal facility, 55 it being only necessary to insert the bottom cup of the stack through the opening through the band, in loading the tube.

The tube 2 is preferably provided with a slotted finger opening 8 for assisting in 60 placement of the receptacles.

The construction and operation of the invention will be readily understood and appreciated from the foregoing description.

It is extremely simple and convenient and 65 most economical. Should the elastic band

5 become damaged or reduced in elasticity, it may be dispensed with and a new band replaced at minimum cost. The band itself, because of its nature and tight grasping engagement around the bottom of the tube, 70 will maintain itself fixedly in position during continued operation. It is equally easy to adjust it very accurately to the desired position and properly distended middle opening, so that the device may be applied and 75 used by any one without the exercise of any special skill.

The size, proportions, thickness, degree of elasticity, or other features of the invention may be easily and accurately determined and 80 adopted, and the diameter of the tube may be made to suit the dimensions of the receptacles to be delivered, either exactly or approximately, while the entire mechanism may be changed or varied in different details, or combined with any supplemental storage or other means by the skilled mechanician, without departure from the scope 85 of the following claims.

What I claim is:

1. In combination with a receptacle holding and delivery tube, an elastic band having an upper stretched portion gripping the tube and capable of being shifted thereon whereby to expand or contract the terminal opening of the lower portion of the band across the end of the delivery tube to adapt 95 it to resilient engagement with varying size receptacles.

2. In combination with a magazine tube, 100 an elastic band stretched around the lower end of the tube with a portion extending beyond and across it forming an elastic embracing ring capable of diameter variation by adjustment of the band on the tube to resiliently embrace receptacles of varying 105 diameters.

3. In combination with a magazine tube, 110 an elastic band having an upper stretched portion embracing the lower end of the tube and extending by its lower centrally open portion in reduced tension inwardly beyond the terminal of the tube providing a transverse variable size opening for variable size cups by shifting the band on the tube.

4. In combination with the delivery end 115 of a receptacle tube, a surrounding elastic band having an upper portion tensionally engaging the tube and capable of movement thereon and a lower portion extending across the end of the tube in reduced tension and of variable open center diameter whereby to support and release cups of varying 120 diameters.

In testimony whereof I hereunto affix my 125 signature.

CHRISTIAN N. BERGMANN.
